(57) **CLAIM**

The ornamental design for a case for optical lenses, as shown and described.

DESCRIPTION

FIG. 1 is a perspective view of a case for optical lenses showing our new design according to an embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a sectional view taken along line 8-8 of FIG. 6;

FIG. 9 is a bottom perspective view thereof; and,

FIG. 10 is an exploded view thereof.

The alternating length broken lines in the FIG. 10 view show the order of assembly of the components seen within the exploded view, and also form no part of the claimed design.
